LUDWIG DÜRR, OF FRIEDRICHSHAFEN, GERMANY, ASSIGNOR TO THE FIRM: LUFT-SCHIFFBAU ZEPPELIN GESELLSCHAFT MIT BESCHRANKTER HAFTUNG, OF FRIEDRICHSHAFEN, GERMANY.

SILENCER OF INTERNAL-COMBUSTION ENGINES.

Application filed July 2, 1920. Serial No. 393,755.

To all whom it may concern:

Be it known that I, LUDWIG DÜRR, a citizen of the German Empire, residing at Friedrichshafen a/B., Germany, have invented certain new and useful Improvements in Silencers of Internal-Combustion Engines, of which the following is a specification.

My invention refers to internal-combustion engines and more especially to the silencers thereof. It is a well-known fact that the exhaust gases blowing off into the exhaust pipe, still possess a considerable pressure and high temperature. In order 10 to improve the efficiency of the engine, endeavours are made to reduce the pressure and the temperature in the silencer as much as possible. This problem could only be solved very imperfectly hitherto, and this 15 applies more particularly to the case of motors for air-craft, the reason being found in the fact that cooling water is only available in limited quantities and that cooling worth mentioning at all can only be 20 achieved with the aid of long pipe-lines which increase the pressure at expulsion in the cylinder in consequence of their resistance.

It is the object of the invention to create 25 as high as possible a vacuum at the exit opening of the exhaust pipe by utilizing the law about the reciprocal conversion of pressure into velocity known from the ejector water air pump, furthermore, to reduce the back-pressure by this means and to utilize the vacuum created for the purpose of sucking in fresh air. Accordingly 30 the object of the invention is a silencer for internal-combustion engines especially suitable for air-craft, the exhaust-pipe of which is surrounded, at least in the vicinity of its exhaust opening, by a jacket pipe in such a manner that the end opening of the exhaust pipe forms the smaller base and the 35 end opening of the jacket pipe played upon by the exhaust gases, the larger base of a slender frustum of a cone.

In the drawings attached to this specification and forming part thereof, illustrates 40 three modifications of a silencer embodying my invention in a purely diagrammatical manner.

Fig. 1 is a cross-section of a four-cylinder engine and of the silencer belonging to it.

Fig. 2 is the same with a somewhat different arrangement of the silencer, and

Fig. 3 is also the same with another variation in the arrangement of the silencer.

I shall proceed to discuss the arrangement according to Fig. 1 first.

The exhaust openings of four cylinders A, A¹, A², A³, are connected with an exhaust receiver tube D by means of a connecting piece C. The exhaust tube D tapers slightly towards its exit opening d'. It is 55 enclosed in a jacket tube E of slightly larger diameter which projects a considerable amount beyond the exhaust pipe D in the same direction as the flow of the exhaust gases. The end opening of the jacket 60 pipe E through which the exhaust gases flow, is designated by e' and the opposite end e². The cylinders A, A¹, A², A³ and the exhaust receiver tube B are surrounded by a leak-proof casing F at a certain distance 65 and a suitable cooling medium flows through 70 the hollow space G thus created.

Assuming for the present that the jacket 75 tube E does not exist and that there is a certain pressure p in the exhaust receiver 80 tube B, then the exhaust gases blow off directly into the open air through the opening d', i. e., they blow off with atmospheric 85 pressure p and with a velocity v depending in the main on the pressure p . Let us now 90 imagine the exhaust pipe D lengthened beyond d' and widening slightly conically (as indicated in Fig. 1 by the dot and dash-lines) so that e¹ becomes the exit opening. Then the exhaust gases completely fill the 95 whole of the funnel-shaped space between the openings d¹ and e¹ without detaching themselves from the surface of the funnel so long as the opening e¹ does not go beyond a certain multiple of the opening d¹. 100

Now the exhaust gases pass into the open atmosphere through the opening e¹ and, with great approximation, again possess the velocity of exit v provided that the pressure p in the exhaust receiver pipe B 105 has not changed. In the opening d¹ therefore a greater velocity v' is found which has approximately the same proportion to v as is the ratio of sectional area between opening e' and opening d'. An increased 110 ratio between the pressures in the exhaust receiver pipe B and the opening d' respectively, however, corresponds to the in-

creased velocity v' . Therefore, if the pressure p in the exhaust receiver pipe B remains unaltered, a considerable amount of vacuum must be the result at the opening d' . In consequence of the increased sucking off of the exhaust gases there actually soon arises a state of inertia in which the pressure in the exhaust receiver pipe B is smaller than p by a certain amount, whilst at the opening d' a velocity between v and v' can be observed, together with a vacuum corresponding to this velocity. With the dropping of the pressure in the exhaust receiver pipe B, however, the indicated work increases proportionately.

The above conditions remain very nearly unaltered, if the conical extension of the exhaust pipe D is left out and the jacket pipe E which is closed at its backward end e^2 , is added instead. The stream of exhaust gas issuing from d' with great velocity and a considerable vacuum, spreads out to a slender cone, a fact which can be observed without difficulty by employing a transparent jacket pipe, and at the moment of exit from the jacket pipe E approximately possesses a sectional area equal to the area of the opening e' .

The vacuum prevailing in the vicinity of the opening d' of the jacket pipe is utilized for sucking in fresh cooling air either by leaving open the backward end e^2 of the jacket pipe or by providing it with an entrance aperture offering the least possible resistance to the air flowing in. The fresh air flowing along the exhaust pipe D, cools the exhaust pipe and in the space between the openings d' and e' partly mixes with the still warmer exhaust gases, in this way contributing towards the extinction of sparks which might still be contained in the stream of exhaust gases. If there is no need to be intent in a particularly energetic cooling of the exhaust pipe D, the entrance opening e^2 may also be connected with the space G formed by the casing F, the air serving to cool the cylinders A, A¹, A², A³ and the exhaust receiver tube B being made to be sucked off by the exhaust gases blowing off at d' , by this means. Fig. 2 illustrates a silencer arranged to serve this purpose. The entrance opening and the manner of guidance of the cooling air in the space G caused by the casing F, which do not form the object of the invention, are not detailed specially in the illustration.

A still thorough mixing of the exhaust gases with the cooling air and consequently increase in cooling and power of suction can be achieved by designing the exhaust pipe D as a kind of ring-shaped tube (two concentric tubes) as will be perceived from the example illustrated in Fig. 3. This example of a possible manner of construction

differs from the one illustrated in Fig. 1 in the following points: The jacket pipe E which is extended conically in the vicinity of the exit opening e' is deflected at the opposite end to form a tube E³ arranged concentrically within the exhaust pipe D and possessing a smaller diameter than the latter and whose exit opening is situated in the same plane as that of the original exit opening d' . Besides that, the jacket pipe E is joined to the cylinder-casing F by means of a connecting piece H arranged concentrically with the connecting piece C, but having a larger diameter.

From the connecting piece C the exhaust gases therefore enter the ring-shaped hollow space between the tubes D and E³ and through the ring-shaped nozzle J formed by the ends of these tubes, flow into the conical part of the jacket pipe E, where they form a ring-shaped body delimited by two cones. The velocity and the vacuum in the vicinity of the ring-shaped nozzle J are the same as in the example illustrated in Fig. 1, if the various component parts of the construction are selected and designed suitably. The great advantage of the arrangement lies in the fact that the cooling air can not only flow through the tube E³, so that the exhaust gases flowing out of the ring-shaped nozzle J are able to mix with cooler air in the central nucleus as well as the outer periphery, thereby being subjected to particularly energetic cooling. The suction effect, though in a minor degree, is also increased. In the case exemplified it is assumed that fresh air which energetically cools the exhaust pipe, flows through the tube E³ and that the air coming from the engine, i. e., from the space G, flows through the ring-shaped space between the tubes D and E. However, the arrangement can of course easily also be modified in such a manner that the double tube D E³ is played upon in the interior as well as on the exterior either by fresh cooling air only or only by air which has previously already served to cool the cylinders A, A¹ A² A³ and the exhaust receiver pipe B.

I claim:

In a device of the kind described in combination, an exhaust pipe and a jacket, open at both ends and connected with the cooling air space surrounding the cylinders, surrounding the free end of said pipe with a clearance and extending beyond it, the diameter of the end opening of said pipe being smaller than the diameter of the end opening of said jacket.

In testimony whereof I affix my signature.

LUDWIG DÜRR.
